UNITED STATES PATENT OFFICE.

HARRY THAYER KINGSBURY, OF KEENE, NEW HAMPSHIRE.

DESIGN FOR A TOY-WAGON BODY.

SPECIFICATION forming part of Design No. 35,117, dated September 17, 1901.

Application filed August 6, 1901. Serial No. 71,109. Term of patent 7 years.

To all whom it may concern:

Be it known that I, HARRY THAYER KINGSBURY, a citizen of the United States, residing at Keene, in the county of Cheshire, State of New Hampshire, have invented and produced a certain new and original Design for Toy-Wagon Bodies, of which the following is a description, reference being had to the accompanying drawing and to the letters of reference marked thereon.

My invention relates to a new and original design for toy-wagon bodies; and it consists in a toy-wagon body of the shape and configuration hereinafter described.

15 The drawing represents a perspective view of the toy-wagon body embodying my design.

In this drawing, A represents as a whole the wagon-body, having at its forward end the upwardly-projecting part B and at its 20 rear the upwardly-projecting part C, the two projecting parts being connected by the corrugated side bars D, which are connected

with the body of the wagon by cross-pieces E. The sides of the wagon-body are provided with two central openings a and with the 25 openings at each end b of the shape shown with the downwardly-projecting lugs c.

The leading feature of the invention consists in a wagon-body having the corrugated side pieces with the openings and the upwardly-projecting forward and back pieces, one being higher than the side pieces and the other lower than the same.

Having thus described my invention, what I claim, and desire to secure by Letters Patent, is—

The design for a toy-wagon body; substantially as shown and described.

In testimony whereof I affix my signature in presence of two witnesses.

HARRY THAYER KINGSBURY.
